UNITED STATES PATENT OFFICE.

HOWARD W. DUNBAR, OF NEWARK, NEW JERSEY, ASSIGNOR TO WESTERN ELECTRIC COMPANY, OF NEW YORK, N. Y., A CORPORATION OF ILLINOIS.

INDICATOR FOR TELEPHONE SWITCHING APPARATUS.

1,012,066.

Specification of Letters Patent. Patented Dec. 19, 1911.

Application filed April 8, 1910. Serial No. 554,158.

To all whom it may concern:

Be it known that I, HOWARD W. DUNBAR, citizen of the United States, residing at Newark, in the county of Essex and State of New Jersey, have invented a certain new and useful Improvement in Indicators for Telephone Switching Apparatus, of which the following is a full, clear, concise, and exact description.

10 My invention relates to telephone switching appliances of the type having a pair of switch-actuating keys and more particularly to switching appliances having self-retracting keys which require additional indicating devices, and its object is to provide a mechanical indicating device for use with a telephone switching appliance having a pair of self-retracting keys which will give the operator a visual indication of the key last actuated, which shall be of few parts, cheap to manufacture, readily applied to the frame of the appliance, and when so applied shall occupy little space thereon.

In accordance with this invention, a visual 25 mechanical indicator is arranged to be associated with or applied to a telephone switching appliance embracing a pair of switch-actuating keys, and comprises a target slidable in a channel in the top of the frame between said keys, the target being arranged to be moved by either of said keys to assume alternative positions of display to indicate which key of the pair was last actuated. A very compact and easily-assembled structure of this sort is secured by providing an actuating lever pivoted upon a horizontal axis below the table or frame, the upper end of said lever engaging the target, and suitable connections between the lever and keys being provided. The lever is preferably pivoted in a bracket which may be readily mounted upon the side of the vertical leg of the frame which supports the switch springs.

40 The accompanying drawings illustrate the invention applied to a telephone switching appliance having a pair of rocking levers, wherein—

Figure 1 is a side elevation partly in section; Fig. 2 is a plan; Fig. 3 is a fragmentary sectional elevation on line 3—3 of Fig. 2; Fig. 4 is a sectional view on line 4—4 of Fig. 1; and Fig. 5 indicates a series of perspective views of the lever and its support-

ing bracket, as well as the slidable indicating plate and its mounting.

The key shown comprises two U-shaped metallic units 1, 2, each bridged at the base by metallic members 3, 4, upon each of which is mounted in suitable insulating 55 mountings 5, 6, a set of switch springs 7, 8. Each of said units 1, 2 is clenched in a trough shaped metallic bridge 9 faced with an insulating strip 10. Each set of switch springs 7, 8 has a normal resting contact 11, 12 and an alternate contact 13, 14. The middle switch springs 15, 16 of the respective sets 7, 8 projects above the outer two and the spring 15 is adapted to be deflected by an insulated roller 17 carried by a rocking 60 lever 18 pivoted between the arms of the bridging member 9, while the middle spring 16 of the set of switch springs 8 is adapted to be deflected by a similar roller 19 carried by a rocking lever 20, similarly pivoted 65 between the arms of the bridging member 9. Each of these middle springs is adapted to return the corresponding rocking lever to its normal intermediate position upon the release of the operating pressure. Riding in 70 a channel 21 in the insulating face plate 10 is an indicator 22 somewhat less in length than the channel, and of less thickness than the depth of said channel. Bridging this 75 channel and secured by screws 23, 24 to the face plate 10 is an escutcheon plate 25 having two openings 26, 27 serving as windows and before either of which the indicator 22 is adapted to show in one of its alternate 80 positions. A transparent protecting shield 28 lies between the said escutcheon plate and the indicator. In the center of the indicator 22 is an opening or slot adapted to accommodate 85 a finger 29 of an angle piece 30 frictionally pivoted by the spring washer 31 and screw 32 to a right angled extension 33 of a bracket 34 secured by screws 35, 36 to the inner side of the unit 1. This angle piece 30 has an arm 40 adapted when the indicator is exposed at the window adjacent 90 the right hand lever to be engaged, upon the actuation of lever 20, by the lug 38 carried upon its cam portion 39 to rotate said angle piece, whereupon its finger 29 shifts the indicator 22 to the window 26 adjacent 95 the left hand lever 18. Similarly a lug 37 of said angle piece 30 is adapted after the indicator has been so moved and is exposed 100 105

- before window 26 adjacent lever 18, as shown in Fig. 3, to be engaged by a lever 41 frictionally pivoted to the cam portion 42 of lever 18, whereupon the finger 29 shifts the indicator back again to its former position before the window 27 adjacent lever 20. It will thus be evident that upon the actuation of either set of switch springs 7 or 8 by its corresponding lever 18 or 20, the target 22 shows at the window adjacent the opposite lever and by having this target a contrasting color, for instance white, since the face plate shown is black, the operator will be enabled to determine at a glance which of the two levers she had last actuated if it becomes necessary that she operate the same one again.
- Having thus described my invention, I claim:
- 20 1. In combination with a telephone switching appliance having a pair of switch-actuating keys, a supporting frame, indicating mechanism comprising a target slidable in a channel in said frame and capable of being displayed in alternative positions, a lever engaging said target, and connections between said lever and keys whereby the actuating movement of the keys is transmitted to said target to cause it to assume one of its alternative positions to indicate the key last actuated.
- 25 2. In combination with a telephone switching appliance having a pair of switch-actuating keys, a supporting frame, indicating mechanism mounted upon said frame comprising a target capable of assuming alternative display positions, a lever mounted upon said frame to rotate about a horizontal axis and adapted to displace said target, and connections between said lever and keys whereby the actuating movement of the keys is transmitted to said target.
- 30

ating keys, a supporting frame, indicating mechanism mounted upon said frame comprising a target capable of assuming alternative display positions, a lever mounted upon said frame to rotate about a horizontal axis and adapted to displace said target, and connections between said lever and keys whereby the actuating movement of the keys is transmitted to said target.

3. In a key structure, the combination with a mounting frame, sets of switch springs mounted thereon, a pair of rocking levers for actuating said springs, an insulated face plate for said frame having a channel located between said keys, an escutcheon plate covering said channel and having a pair of windows, an indicating plate slidable in said channel and adapted to be displayed at either of said windows, an angle piece pivoted to said frame to rotate about a horizontal axis and having a finger extending through openings in said frame and insulating face plate and engaging a slot in said indicating plate, and connections between said lever and keys whereby the indicator remains displayed at the window adjacent the key opposite that last actuated.

In witness whereof, I hereunto subscribe my name this 6th day of April A. D., 1910.

HOWARD W. DUNBAR
